(57) **CLAIM**

The ornamental design for a digital camera, as shown and described.

DESCRIPTION

FIG. 1 is a front, right and top perspective view of a digital camera, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 8 is a bottom plan view thereof.

FIG. 9 is an enlarged portion of encircled portion labeled, “FIG. 9,” in FIG. 1; and,

FIG. 10 is an enlarged portion view of encircled portion labeled, “FIG. 10,” in FIG. 1.

The broken lines shown in the drawings are included for the purpose of illustrating portions of the digital camera that form no part of the claimed design.

The dot-dash broken lines depict the boundaries of the enlargements that form no part of the claimed design.

1 Claim, 10 Drawing Sheets
